The ornamental design for a broom, as shown and described.

DESCRIPTION

FIG. 1 is a perspective view of a broom showing my new design;

FIG. 2 is a front elevational view thereof;

FIG. 3 is a side elevational thereof taken from the right side of FIG. 2;

FIG. 4 is a rear elevational view thereof;

FIG. 5 is a side elevational view thereof taken from the side opposite of FIG. 3;

FIG. 6 is a top plan view thereof;

FIG. 7 is a bottom plan view thereof;

FIG. 8 is an enlarged scale perspective view, taken from FIG. 1, of the T-shaped head;

FIG. 9 is an enlarged scale elevational view, taken from FIG. 2, of the T-shaped head;

FIG. 10 is an enlarged scale elevational view, taken from FIG. 3, of the T-shaped head;

FIG. 11 is an enlarged scale top view, taken from FIG. 6, of the T-shaped head; and,

FIG. 12 is an enlarged scale perspective view, taken from FIG. 1, of the hand grip portion of the handle.

FIGS. 8, 9, 10, and 12 are partially shown for ease and clarity of illustration.
